UNITED STATES PATENT OFFICE.

JOSEPH SNYDER AND CHARLES E. LYTER, OF HARRISBURG,
PENNSYLVANIA.

CAR-COUPLING.

SPECIFICATION forming part of Letters Patent No. 766,738, dated August 2, 1904.

Application filed March 7, 1904. Serial No. 196,827. (No model.)

To all whom it may concern:

Be it known that we, JOSEPH SNYDER and CHARLES E. LYTER, citizens of the United States, residing at Harrisburg, in the county 5 of Dauphin and State of Pennsylvania, have invented certain new and useful Improvements in Car-Couplers; and we do declare the following to be a full, clear, and exact description of the invention, such as will enable others skilled 10 in the art to which it appertains to make and use the same.

This invention relates to car-couplers of the Janney type; and it has for its object to provide a simple, durable, and easily-operated 15 coupler of few parts so constructed and arranged as not to be liable to break or become disarranged when in use; and it consists of the parts and combinations of parts hereinafter described and claimed.

20 In the accompanying drawings, forming a part of this specification, Figure 1 is a longitudinal vertical section on the line 1 1, Fig. 2. Fig. 2 is a horizontal section through the draw-head. Fig. 3 is a transverse vertical section 25 on line 3 3, Fig. 2. Fig. 4 is a detail view of the locking-pin; Fig. 5, a detail view of the trigger-pin; Fig. 6, a detail view of the locking-pin from the side opposite that shown in Fig. 4, and Fig. 7 a detail perspective view 30 of the knuckle-tailpiece.

Similar letters refer to similar parts throughout all the views.

Referring to the drawings, A represents the draw-bar, B the draw-head, and C the knuckle, 35 of our improved coupler.

The general arrangement and construction of the parts named may be similar to the well-known type of coupler named above, except as hereinafter noted. The knuckle-tailpiece 40 c is formed with a hook-shaped end, as at c', which is adapted to enter a slot or opening b, formed in one of the side walls of the draw-head in rear of the hinge-pin on which the knuckle swings. The object of this construction 45 of the knuckle-tailpiece is to provide a secure connection between the knuckle and the draw-head in the event of the breaking of the hinge-pin, the hook c' in that event engaging in the slot or opening b, and thus pre-

venting the knuckle being drawn out or dropping while the knuckle is in its closed position. The knuckle-tailpiece is also formed with a vertical projection c² at its end, the top of which is inclined or beveled to correspond to the shape of the top of the opening in the draw-head in which the knuckle-tailpiece works. The rear face of the projection c² conforms to the shape of the end of the tailpiece, and its front or forward faces or sides c³ c⁴ extend at an angle from each other toward the side edges of the tailpiece, the face c³ being adapted to engage or abut against the side of the locking-pin D in order to prevent the knuckle swinging out too far.

The upper half of the draw-head is cast with 65 the enlarged portion b², through which a square vertical opening b³ is formed, at the lower end of which at one side is formed the recess b⁴, Fig. 3, while in the lower half of said draw-head is formed a triangular-shaped opening 70 b⁵ in line with the opening b³.

The locking-pin D is formed with a square body adapted to fit in the opening b³ and with a triangular-shaped end portion d, adapted to fit within the opening b⁵. At its upper end a 75 perforated ear d' is formed on the locking-pin in order to provide for the attachment of a chain or lever to connect it with uncoupling-lever, and a flange d² is formed below said ear d' on the pin to limit the downward movement 80 of the pin when it drops to lock the knuckle.

In one side of the locking-pin a longitudinal groove d³ is formed, the bottom of which is somewhat irregular in shape—that is to say, that it is cut out, as at d⁴, in an inclining direction, so as to provide a groove with a varying depth for a purpose to be described. (See Fig. 3.) At the lower end of the body of the locking-pin at one side is formed a recess or opening d⁵, which extends into the 90 groove d³. A trigger F of irregular shape and conforming at one edge to the shape of the bottom of the groove d³ is pivotally suspended in said groove, said trigger being bent or cast with the inclined or beveled portion f' 95 at its rear edge and being formed with the right-angled toe f², the latter being adapted to enter the opening d⁵, as clearly shown in

Fig. 3. A trigger-pin G is inserted through an opening therefor formed in the enlarged portion b^2 of the draw-head and is secured by a split key, and its reduced end enters the groove d^3 and engages or abuts against the rear edge of the locking-pin, so that the upward movement of said locking-pin will cause the trigger F to press against the pin G and be thus forced toward the bottom of the groove 5 d^3 and its toe f^2 to be pushed into the opening d^5 until its extreme end projects beyond the side of the locking-pin and it is in position to enter the recess l^4 , and thus limit the upward throw of the locking-pin when the same 10 is raised or lifted to release the knuckle, and thus uncouple the couplers. When the knuckle is swung out after being uncoupled or released, the end of the body of the locking-pin rests 15 on the tailpiece and the projection e^2 engages the side of said pin and incidentally forces the toe of the trigger back into the slot or opening d^6 , so that its end is flush with the face of the locking-pin. The trigger-pin G, as clearly 20 shown in Fig. 5, is formed with shoulders g , which rest against the edges of the groove d^3 , while its reduced and beveled end g' enters 25 said groove and is in position to engage the inclined or beveled portion of the trigger F in order to force the trigger inwardly, as 30 above described.

The trigger F, as clearly shown in Fig. 3, is hung or pivotally mounted in the groove d^3 on a pin e , passing through the locking-pin and through an opening in the end of the trigger, so that the tendency of the trigger is to 35 normally hang as shown in Fig. 3—that is to say, wholly within the groove and with the end of the toe f^2 in line with the front face of the locking-pin and to gravitate or swing 40 into such position when permitted so to do by the pin G.

The knuckle may be released by any of the usual devices for lifting the locking-pin, and in the event of the locking-pin being

frozen or its easy movement retarded for other 45 reasons a smart blow on the triangular end thereof will quickly release it.

Having thus described our invention, what we claim as new, and desire to secure by Letters Patent, is—

1. A car-coupler comprising a draw-head, a knuckle, a vertically-movable locking-pin, a trigger for engaging the draw-head, and means for operating the trigger when the locking-pin is lifted in order to limit the upward movement of the locking-pin to its 50 unlocking position.

2. A car-coupler comprising a draw-head, a knuckle pivotally mounted therein and having a tailpiece provided with a vertical projection, a vertically-movable locking-pin, a trigger for limiting the upward movement of said locking-pin, and a trigger-pin for operating said trigger.

3. A car-coupler comprising a draw-head 65 having a square vertical opening for the locking-pin, and a recess adjacent said opening, a horizontally - swinging knuckle having a vertical projection on its tailpiece, a vertically-movable locking-pin having a longitudinal 70 groove formed therein and an opening at the lower end of said groove, a trigger having a right - angled toe suspended in said groove, and means for swinging said trigger in said groove when the locking-pin is raised.

4. A car-coupler comprising a draw-head, a knuckle, a vertically-movable locking-pin, a trigger carried by said pin, a fixed pin for operating said trigger to cause it to engage the draw-head to limit the upward movement 80 of said locking-pin to its unlocking position.

In testimony whereof we affix our signatures in presence of two witnesses.

JOSEPH SNYDER.
CHAS. E. LYTER.
